UNITED STATES PATENT OFFICE

128,611

DESIGN FOR A CULINARY TONGS

Lee O. Barnes, Portland, Oreg.

Application June 2, 1941, Serial No. 101,263

Term of patent 7 years

To all whom it may concern:

Be it known that I, Lee O. Barnes, a citizen of the United States, residing at Portland, in the county of Multnomah and State of Oregon, have invented a new, original, and ornamental Design for a Culinary Tongs, of which the following is a specification, reference being had to the accompanying drawing, forming part thereof.

Figure 1 is a perspective view of a culinary tongs, showing my new design.

Figure 2 is an end elevational view thereof.

I claim:

The ornamental design for a culinary tongs, as shown.

LEE O. BARNES.
